UNITED STATES PATENT OFFICE.

E. F. LEWIS FRITZ, OF CHICAGO, ILLINOIS.

SUPPORTER.

Application filed September 30, 1922. Serial No. 591,628.

To all whom it may concern:

Be it known that I, E. F. LEWIS FRITZ, a citizen of the United States, and a resident of the city of Chicago, county of Cook, 5 and State of Illinois, have invented certain new and useful Improvements in Supporters, of which the following is a specification.

My invention relates to novel improvements in supporters having for its principal object the provision of an improved construction which will be highly efficient in use and economical in manufacture.

Among the silent objects of the invention is the provision of a supporter especially 15 adapted for use as a breast support which will retain the contour of the breasts and be comfortable to wear.

Other objects will appear hereinafter.

The invention consists in the combinations 20 and arrangements of parts hereinafter described and claimed.

The invention will be best understood by reference to the accompanying drawings forming a part of this specification, and in 25 which,

Fig. 1 is a side elevational view of the invention,

Fig. 2 is a front elevational view of the same,

Fig. 3 is a sectional detailed view taken substantially on line 3—3 of Fig. 2, and

Fig. 4 is a top plan view of the invention.

In carrying the objects of the invention into effect the preferred form of construction comprises two metallic telescopically arranged parts 5 and 6 provided with means for holding the parts in the proper adjusted position, said means comprising a protuberance 7 formed on the part 5 and adapted to 35 engage a depression 8 formed in the part 6. The parts 5 and 6 are each formed with the depending semi-circular portion 9 which primarily passes around the lower portion of the breasts and serves to support the same. The depending semi-circular portions 9 each carry a covering 10 of suitable material which, when the supports are in position are adapted to cover the lower portion of the breasts. If desired a netting 11 can be secured to each of the coverings 10 by suitable means to serve to hold the breasts within the pockets formed by the covers to prevent movement of the breasts. The supports are arranged and held in position 50 by a strap 12 the opposite ends of which pass through elongated slots 13 formed in

the outer end of the parts 5 and 6; neat bows 14 being formed by the strap ends to prevent the strap from disengagement with the slots. The strap 12 is adapted to pass under the shoulder pits and extend around the body of the wearer. Secured by suitable means to the strap 12 are shoulder straps 15 adapted to pass over the shoulders of the wearer to hold the strap 12 in proper 65 position.

The supporter herein set forth and described will be a great value to the wearer in many obvious respects and can be manufactured of light material such as aluminum or the like at a very nominal cost.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of 75 the appended claims.

Having described my invention, what I claim as new and desire to secure by Letters Patent is:

1. In combination with a strap adapted to 85 pass around the body of the wearer and shoulder straps attached thereto, a support having slots formed in the ends thereof and provided with depending portions extending around the lower portion of the breasts, the body strap having its ends taken through the slots and fixed to said support, and breast receiving pockets including upper 90 portions of net work.

2. In combination with a strap adapted 95 to pass around the body of the wearer and shoulder straps attached thereto, a support including parts having end portions telescopically arranged together and having slots formed in the ends thereof and provided with depending portions extending around the lower portion of the breasts, the body strap having its ends taken through the slots and fixed to said support, and breast receiving pockets including upper 100 portions of net work.

In testimony whereof I have signed my name to this specification in the presence of a subscribing witness.

E. F. LEWIS FRITZ.

Witness:

CLARENCE E. THREEDY.
